UNITED STATES PATENT OFFICE.

GEORGE H. DUNCAN, OF SCHENECTADY, NEW YORK.

DESIGN FOR A BADGE OR SIMILAR ARTICLE.

SPECIFICATION forming part of Design No. 32,270, dated February 27, 1900.

Application filed December 23, 1899. Serial No. 741,479. Term of patent 14 years.

To all whom it may concern:

Be it known that I, GEORGE H. DUNCAN, a citizen of the United States, residing at Schenectady, in the county of Schenectady and 5 State of New York, have invented and produced a new and original Design for Badges or Similar Articles, of which the following is a specification, reference being had to the accompanying drawing, forming part thereof.

10 In the drawing is shown in front elevation a badge embodying my invention.

The leading feature of the design is the figure of an eagle having outspread wings, with the head of an Indian located above it.

15 Referring to the drawing by letter, G' represents a disk-like body, and appearing thereon is the eagle A, having outspread wings B. Located in front of the left-hand wing is a tomahawk C, and in front of the right-hand

wing is a war-club D. In the claws of the eagle 20 is a bow and arrow E, and in the beak is a ribbon or streamer F. Situated above the eagle and located between its outspread wings is the head G of an Indian.

The design is applicable to badges, club 25 emblems, stationery, &c.

Having described my invention, what I claim as new, and desire to secure by Letters Patent, is—

The design for a badge or similar article, 30 substantially as shown and described.

In testimony whereof I have signed my name to the specification in the presence of two subscribing witnesses.

GEORGE H. DUNCAN.
